UNITED STATES PATENT OFFICE.

GEORGE F. EDWARDS, OF ALAMEDA, CALIFORNIA.

AUTOMOBILE LICENSE-PLATE HOLDER.

Application filed July 29, 1925. Serial No. 46,726.

The present invention relates particularly to a plate containing cut out characters visible in the day and illuminated at night by light rays passing through the cutouts of 5 the particular characters, and more particularly to the plate, the cutout characters of which are embossed and are clearly outlined parallel with their cutout edges.

A further object is to provide a structure 10 in the form of an illuminating or reflecting box, one wall of which is formed by the plate, the box containing a lateral extension in communication with the interior of the box, there being a single lamp, common to 15 both the box and extension, and there preferably being provided a colored bullseye disposed to close the extension opening and lying parallel with the plate.

A further object is to provide a novel 20 form or plate mounting means and a novel form of bullseye mounting means, together with a structure for rigidly supporting, bracing and mounting the box on a support.

While the invention is illustrated and 25 characterized as being used for a vehicle license plate, it is to be understood that the same is adaptable to any use to which it may be put.

In the drawings—

30 Fig. 1 is a view in front elevation of the preferred embodiment of my invention.

Fig. 2 is a top plan view partly in broken section.

Fig. 3 is a vertical section on line 3—3 of Fig. 1.

Fig. 4 is a transverse sectional view through a portion of one of the embossed characters on the line 4—4 of Fig. 1.

Fig. 5 is a sectional view of the locking means, taken on line 5—5 of Fig. 2.

Fig. 6 is a horizontal sectional view through the lateral box extension and the bullseye, taken on line 6—6 of Fig. 1.

In the drawings, wherein like characters of reference designate corresponding parts, the numeral 1 indicates a bracket having lateral arm extensions 2 and a downwardly inclined supporting arm extension 3. The arms 2 are curved as in Fig. 2 and the same 50 are secured as at 4 to an arcuately curved rear wall 5 of a reflector box 6, the bottom wall 7 of which is downwardly inclined and the top wall 8 of which is upwardly inclined. The free edges of the walls 7 and 8 55 and one end of the wall 6 are channeled as at 9 to receive the opposite edges and one

end of a plate 10 which is moved longitudinally endwise into the edges to form a closure for the open face of the box.

The plate 10 is held in position by a locking pin 11 carried on a spring 12 and passing through a small aperture in the end of the plate, this being clearly illustrated in Fig. 5.

The surface of the plate is provided with 65 embossed character designs 13, the present illustrated form being numbers. The embossed designs are cut out as at 14 and the edges of the embossing, beyond the cut out portions, are distinctively outlined as at 15, 70 thus a character which can be readily seen in the day, due to its embossed construction and its outlined design, and which can be readily seen at night due to the opening therethrough is provided in the surface of 75 the plate.

To preclude foreign material from passing through the openings in the cut out designs, the plate is backed with a transparent sheet 16, celluloid, for example. 80

Extending upwardly from the reflector box is a lateral extension 17 of substantially semi-conical form, the rear wall 18 of which is upwardly inclined and the open rear face 19 of which is closed preferably by a colored 85 bullseye 20, the same having peripheral extensions 21 adapted for reception within recesses 22, on the rotary movement of the bullseye to lie behind the retaining wall 23, as illustrated in Fig. 1. 90

A single lamp of illuminating means 24, illustrated as being illuminated by electricity from wires 25 projects into the lateral extension 17 and the box 16, the light rays liberated thereby serving to reflect from 95 the walls of the box and the extension and illuminate the character outlined designs and bullseye 20.

The particular structure illustrated is adaptable for ready attachment to the rear 100 of motor driven vehicles, as the same constitutes a license plate holder and a tail light, but the plate with its distinctive characters is adapted for many uses, such as house numbering and the like. 105

I claim:—

In combination with a plate provided on one face with character designs cut away to provide transparent portions; a reflector box having an open wall, said wall provided 110 with opposing channeled edges for reception of said plate edges on its endwise move-

ment thereinto to close said box wall opening; one of said channeled ends provided with an aperture; the end of the plate provided with an aperture adapted for alignment with the first mentioned aperture; a spring mounted upon said channeled end; a pin carried by said spring and adapted for yieldable holding thereby within said aligned apertures for detachably retaining the plate within the channeled edges; an attaching bracket secured to the box, said

box provided with a lateral extension carried thereabove with its interior communicating with the interior of the box and provided with an opening parallel with the open box wall; a colored bullseye for closing the latter opening, and a single illuminating means within said box and common to said plate and bullseye.

In testimony whereof I have signed my name to this specification.

GEORGE F. EDWARDS.
